UNITED STATES PATENT OFFICE

WILLIAM C. KENNEY AND GEORGE M. KENNEY, OF CRANSTON, RHODE ISLAND,
ASSIGNORS TO KENNEY MANUFACTURING COMPANY, OF AUBURN, RHODE ISLAND,
A CORPORATION OF RHODE ISLAND

CURTAIN FIXTURE

Application filed November 18, 1931. Serial No. 575,820.

This invention relates to brackets for curtain, drapery, portière, traverse and like rods adapted to suspend a curtain over the door, window or other opening to be draped.

Such rods have been made in varying cross-sections, beginning with the round rod of the early prior art, later modified to the familiar C-shaped rod still on the market, and now offered to the trade in U-shape form under the George M. Kenney patent of August 6, 1929, No. 1,723,975. Such rods have also been made either straight (for inside attachment between the inner faces of the door, window, or other casing), or with curved elbow ends (for outside attachment to the outer faces of such casing).

Each type of rod has required its own particular supporting bracket, and such brackets have taken various forms. Our invention contemplates various forms but is especially adapted to the U-shape to which we refer by way of illustration.

The rods in question as illustrated by those of U-shaped cross section have proven to involve an individual problem and require special centering, balance and support. Prior art suggestions are entirely incapable of use with such rod, for the reason that the novel cross-section of such rod introduces special problems of proportion not present in the older types of rod and hence not provided for by the brackets especially designed for use with such older rods.

To the end, therefore, of providing for the first time in the art a bracket which can be interchangeably used with both right and left ends of a curtain rod, or the like, and with both inside and outside rods, and which bracket moreover is especially designed properly to center, balance and support all such rods as the characteristic Kenney U-shaped rod, we have devised our present invention.

According to it, our bracket is not only capable of such interchangeable use but is so constructed and designed as to permit the rod to be engaged and disengaged with a straight line motion rather than requiring an initial tilting of the rod relative to the bracket, as has been true of certain prior art brackets. At the same time it provides for the balanced

support of the rod on a conforming bearing surface which is at once broad, ample and stable, instead of relying upon the rather uncertain engagement of a slender hook or prong on the bracket with a narrow hole or slot in the rod to furnish such support, as heretofore in the art, with resultant liability to the rod to waddle on such hook or to disengage therefrom by accidental upward lifting movement.

In other words, our concept contemplates a bracket stably and reliably to support the rod at all times and under all conditions of use. Such brackets positively prevent inadvertent disengagement of the rod by accidental lifting movement as well as any tendency of the rod to wobble or shift laterally, due to draft or vibration, and which tendency was not effectively met where the penetration of a prong or hook on the bracket through alined holes in the rod edges was depended upon to hold the rod securely to the bracket.

In the accompanying drawings we illustrate a form of bracket which we have found especially satisfactory for use with the U-shaped rod, such bracket being also a form which is at once simple and convenient of installation and use and relatively inexpensive of manufacture.

In these drawings:—

Fig. 1 is a fragmentary perspective of an inside telescopic rod of characteristic Kenney U-shape, although such rod need not, of course, be a telescopic rod, nor need it be an inside rod, but may be an outside rod.

Fig. 2 is a plan view showing an installation consisting of one or more, here shown as two, inside rods, it being understood that the installation may however comprise any practicable number of rods, as one, two, or three.

Fig. 3 is a similar view of a characteristic installation consisting of two outside rods.

Fig. 4 is a perspective view of one of the rod supporting brackets shown in Figs. 2 or 3, removed.

Fig. 5 is a sectionalized showing of a rod and its supporting brackets in installed position, and for the purposes of the view may be

considered as being a longitudinal section through one of the rods and its brackets shown in Fig. 2.

Fig. 6 is an elevation of Fig. 5.

5 Fig. 7 is a cross-section on the line 7—7, of Fig. 6, and

Figs. 8 and 9 show brackets particularly adapted for single and double installations of outside traverse rods.

10 Referring first to Fig. 1. We have illustrated a Kenney rod of U-shaped cross section presenting a pair of lateral walls 1 connected at their upper edges by a top wall 2 which may be arched as shown and terminating at their lower edges in spaced inturned flanges 3, which at their points of bend away from the side walls 1 are preferably rounded as indicated at 4.

The U-shaped rod may be a single length 20 of rod or may be made in telescopic sections A and B, either with or without the curved ends or elbows C in Fig. 3 and either with or without the interposed coupling members D (Fig. 3) of corresponding cross-section.

25 Similarly, one or more rods may be used, as shown in Figs. 2 and 3. In Fig. 2 the rod or rods are inside rods, being attached to the inner faces I of the window, door or other casing frame F. In Fig. 3, the rod or rods 30 are outside rods, being attached to the outer faces O of the frame F.

In any instance, and with any type of rod, the same attaching brackets may be used. Where multiple rods are employed, the bases 35 10 of the brackets carry a corresponding number of rod supports, indicated generally at 11.

A single bracket, usable interchangeably with the right or left ends of a rod, is detailed in Fig. 4.

Such bracket includes the attaching base 10 which may conveniently be slightly arched between its ends as indicated at 12 and provided at its ends with holes 13 for the entrance of suitable attaching screws, the arched formation 12 enabling the rod end to clear the head of the upper attaching screw when the bracket is affixed in position.

The rod support indicated generally at 11-50 projects horizontally from said base 10 substantially centrally thereof. Such support includes a pair of generally U-shaped formations 14 and 15 which together define an open-topped double U-shaped cavity or recess of 55 reversed contour to the U-shape of the rod for the reception of the rod end as well as constituting means for preventing accidental vertical displacement and lateral wobbling of the rod.

60 The rod end is inserted into said cavity or recess from above with a simple straight line sliding movement, the formations 14 and 15 presenting centrally of the cavity or recess a centering and locking formation 16 65 which may conveniently be of prong-like

character and which is adapted to be penetrated through an elongated slot 17 in the connecting wall 2 of the rod.

The free end of this prong may be split as at 18 to afford a pair of spring locking lips 19 which are compressed by the inner faces of the flanges 3 when the slot 17 is aligned with said prong and the rod pushed down over the same, and thereafter to spring apart to lock the rod against accidental disengagement from the prong by upward vertical lifting movement.

Structurally such recess and prong may be conveniently formed by two properly bent strips of metal at each vertical edge of the base 10. These are anchored in any suitable manner, as by welding to the base, or may even be integral therewith.

Each strip is itself U-shape, presenting an outer wall indicated at 14 or 15 and an inner wall indicated at 14' or 15', connected by a rounded bottom wall 14a, 15a.

The inner walls 14', 15', abut each other internally of the double U-shaped recess or cavity thus provided, being extended above the upper horizontal edge of the formations 14 and 15 as the centering and locking prong 16.

The bracket is so dimensioned and the construction is such that instead of relying upon the prong 16 itself to carry the weight of the rod and curtain, as heretofore in the art of pronged brackets, the prong is simply a guide for the rod in seating the same in the U-shaped recess of the bracket and a locking device for preventing accidental disengagement thereof by upward lifting motion.

Instead, the rod bottoms on the bottom walls 14a, 15a, as clearly shown in Fig. 7, the rounded flanges 3 thereof resting on and being supported by the rounded surfaces of said recess walls. Thus, the entire weight of the rod and curtain is carried by the formation 14 and 15.

Moreover, the outer walls of these formations restrain the rod against any tendency to wobble laterally on the prong 16, providing a snugly conforming encirclement for substantially the entire depth of the rod end, as best appears in Figs. 6 and 7.

In order to compensate for any difference in height where a telescopic rod having an inner section A of smaller diameter and an outer section B of larger diameter is employed (see Fig. 1), and thus to avoid any looseness of fit regardless of which end of the rod is inserted into the bracket, we preferably form a short depressed channel bead 20 longitudinally in the top wall 2 of the rod adjacent the slot 17 in the outer rod section B as is clearly shown at the right hand end of the rod in Fig. 1. (See also Figs. 5 and 7.)

In the form of Figs. 8 and 9, which may be regarded as a modification for single or double outside rods, the attaching base 10 is pro-

vided with a right-angled extension 10' from which the rod engaging formation or formations 11 laterally project. The parts of the brackets of Figs. 8 and 9 are duplicates of and 5 interchangeable with those of the bracket of Fig. 4.

Various modifications in the construction and operation of our device may obviously be resorted to if within the spirit and scope 10 of our invention without departing from the limits of the appended claims.

What we therefore claim and desire to secure by Letters Patent is:—

1. A supporting bracket for a U-shaped 15 rod adapted interchangeably to receive either the right or left end of the rod, comprising an attaching base, and a formation projecting therefrom and defining a U-shaped receiving recess in which the rod is adapted to be entered from above, said formation having a guiding and locking prong over which the rod is adapted to be centered as it entered into said recess, said prong lying in a plane substantially parallel with the sides of the 20 recess.

2. A bracket as claimed in claim 1, wherein the U-shaped receiving recess for the rod is constituted by a pair of spaced strips extending laterally from the base, each strip being 30 of U-form and together defining a double U.

3. A bracket as claimed in claim 1, wherein the free end of said prong is formed as a pair of yieldable locking lips adapted to be compressed by the rod as the rod is entered over 35 said prong and thereafter to return and lock the rod against accidental disengagement from the prong by an upward lifting movement.

4. A supporting bracket for a rod of deep 40 vertical channel section adapted interchangeably to receive either the right or left end of the rod, comprising an attaching base, and a formation projecting therefrom and defining a receiving recess in which the rod is adapted to be entered from above, said formation having a guiding and locking prong over 45 which the rod is adapted to be centered as it is entered into said recess, said prong lying in a plane substantially parallel with the sides 50 of the recess.

5. A supporting bracket for a U-shaped rod, comprising an attaching base, and a formation projecting therefrom and defining a U-shaped receiving recess in which the 55 rod is adapted to be entered from above, said receiving recess being constituted by a pair of spaced strips extending laterally from the base, each strip being of U form and together defining a double U, the inner walls of said U-shaped strips being brought substantially together to form a guiding and locking prong over 60 which the rod is adapted to be centered as it is entered into said recess, said prong lying in a plane substantially parallel with the sides of the recess.

6. A bracket as claimed in claim 5, wherein the outer walls of said strips constitute a closely conforming encirclement of the rod and restrain it against lateral play in either direction within the recess. 70

7. In a curtain or drapery fixture, the combination with a U-shaped rod, of a supporting bracket having a U-form recess of reversed arrangement to the U of the rod whereby the rod may be inserted into and removed from said recess by simple straight line movement and a centering and locking prong disposed substantially centrally of said recess and adapted for penetrative engagement with said rod, said prong lying in a plane substantially parallel with the sides of the recess. 80

8. A supporting bracket for a rod of deep vertical channel section, said bracket including a projection shaped to define an open top, closed bottom recess of reversed channel section to the channel section of the rod itself whereby the rod may be inserted into and removed from said recess by simple straight line movement from above, and said receiving recess being constituted by a pair of spaced curved strips, the inner walls of said strips being brought together to form a guiding and locking prong over which the rod is adapted to be centered as it is entered into said recess from above, and the outer walls of said strips constituting a closely conforming encirclement of the rod effective to restrain the rod against lateral play in either direction within said recess, said prong lying in a plane substantially parallel with the sides of the recess. 90

9. A bracket as claimed in claim 8, wherein the free end of said prong is formed as a pair of yieldable locking lips adapted to be compressed by the rod as the rod is entered over said prong and thereafter to return and lock the rod against accidental disengagement from the prong by an upward lifting movement. 95

10. A supporting bracket for a rod of deep vertical channel section, comprising an attaching base and a formation projecting therefrom and defining a recess of reverse channel section to the channel section of the rod itself, said recess being open at its top and closed at its bottom whereby the rod may be inserted thereinto and removed therefrom by a simple straight line entering or withdrawing movement, the outer walls of said recess constituting a closely confining encirclement of the rod effective to restrain the rod against lateral play in either direction within said recess, and said formation having a vertically disposed centering and spring locking prong adapted for penetrative engagement with said rod as it is entered into said recess from above and effective to lock the rod within the recess against accidental dislodgement therefrom by a straight line upward lifting movement, said prong lying 110 120 125 130

in a plane substantially parallel with the sides of the recess.

11. A bracket as claimed in claim 10 wherein the recess is of generally W-shape and the locking prong is constituted by the middle leg of the W.

12. A supporting bracket for a U-shaped rod adapted interchangeably to receive either the right or left end of the rod, including a formation of generally W-shape defining an open top, closed bottom recess within which the rod is adapted to be inserted from above by simple straight line entering movement, said formation having a vertically disposed centering and spring locking prong adapted for penetrative engagement with said rod as it is entered into said recess from above and effective to lock the rod against accidental dislodgement therefrom by a straight line upward lifting movement, said prong lying in a plane substantially parallel with the sides of the recess.

13. A supporting bracket for a rod comprising an attaching base and a formation projecting therefrom and defining an open top closed bottom recess into which the rod may be inserted and removed by a simple straight line entering or withdrawing movement from above, said formation having a guiding and locking prong over which the rod is adapted to be centered as it is entered into said recess, said prong lying in a plane substantially parallel with the sides of the recess and terminating at its free end in a compressible locking projection adapted to be engaged by the rod as the rod is entered over said prong and effective to lock the rod against accidental disengagement from the upward lifting movement.

14. A supporting bracket as claimed in claim 13, wherein the prong is included within the walls of said recess and extends vertically of the recess substantially centrally thereof.

15. In testimony whereof we affix our signatures.

WILLIAM C. KENNEY.
GEORGE M. KENNEY.
